UNITED STATES PATENT OFFICE.

ELBERT R. ROBINSON, OF CHICAGO, ILLINOIS.

SWITCH.

No. 866,306.

Specification of Letters Patent.

Patented Sept. 17, 1907.

Application filed February 18, 1907. Serial No. 358,103.

To all whom it may concern:

Be it known that I, ELBERT R. ROBINSON, a citizen of the United States; residing at Chicago, in the county of Cook and State of Illinois, have invented certain new and useful Improvements in Switches; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to railroads, but more particularly to switches, and has for its object to provide a device of this class which will withstand the wear of the rolling stock without deteriorating, to such an extent that the switch will last as long as the rails.

Owing to the nature of switches for railroads they are not as solid as the rails themselves and are much more liable to wear, particularly on account of the action of the flanges of the wheels of the rolling stock on the switch tongue. The result of this wear occasions frequent renewal of the switch tongues and of the rail adjacent thereto.

It is the primary object of my invention to construct a switch which will withstand this wear to such an extent that the life of the switch tongue and adjacent rail is greatly prolonged, thereby obviating the necessity of frequent renewal of the parts.

With this object in view my invention consists in the novel construction of the switch tongue and also in the application of a removable chilled piece of section to the rail immediately adjacent the switch tongue.

Referring to the accompanying drawing: the figure is a plan view of a switch with rail constructed in accordance with my invention.

In the figure, 1 represents the switch, 2 the continuous rail and 3 the intersecting rail.

4 indicates the switch tongue pivoted at 5. The said switch tongue is preferably made of steel having the tapered end portion 6 tempered as illustrated by cross lines.

7 indicates a removable chill arranged in the rail 2 on the inner or flange side thereof. This construction provides for a ready removal of the said chill for replacing the same should the occasion arise.

Having thus fully described the several parts of my invention its operation is as follows: The switch tongue being in the position shown in the drawing, the impact of the flanges of the car wheels is on that portion of the tongue illustrated by cross lines; consequently in the 50 usual construction excessive wear occurs along this portion. By tempering that portion as above described the tongue will last a very long time without showing wear. When the switch tongue is thrown out so as to confine the rolling stock to the continuous track, there 55 is, as of course is clearly understood, a break or gap in the rail opposite the switch tongue, said break or gap occurring at the intersection of the rails. The rolling stock following the continuous rail 2 strikes this break or gap in the opposite rail and has a tendency to cause 60 the flanges on the wheels to strike the continuous rail 2 at a point directly opposite the said break or gap. At this point therefore in the continuous rail I provide the removable chill 7, thereby hardening the rail at this point and obviating the usual wear. 65

Having thus fully described my invention what I claim as new and desire to secure by Letters Patent of the United States is.—

1. A switch for railroads comprising a switch tongue having a portion thereof tempered, and a removable chilled 70 piece or section arranged in the rail adjacent the said switch tongue, substantially as described.

2. A switch for railroads comprising a switch tongue having a portion thereof hardened, and a removable chilled piece or section arranged in the rail adjacent the said 75 switch tongue, substantially as described.

3. A switch for railroads comprising a switch tongue, and a chilled piece or section arranged in the rail adjacent to said switch tongue, substantially as described.

4. A switch for railroads comprising a switch tongue 80 and a rail adjacent said switch tongue, that portion of the rail adjacent the switch tongue being hardened to a greater degree than the remaining portion of the rail, substantially as described.

5. A switch for railroads comprising a rail having a 85 removable chilled piece or section arranged therein, substantially as described.

In testimony whereof, I affix my signature, in presence of two witnesses.

ELBERT R. ROBINSON.
